UNITED STATES PATENT OFFICE

169,656

NUTCRACKER

Herman E. Cox, Norfolk, Va.

Application March 28, 1952, Serial No. 19,101

Term of patent 3½ years

(Cl. D44—1)

To all whom it may concern:

Be it known that I, Herman E. Cox, a citizen of the United States, residing at Norfolk, State of Virginia, have invented a new, original, and ornamental Design for a Nut Cracker, of which the following is a specification, reference being had to the accompanying drawings, forming a part hereof.

Figure 1 is a perspective view of a nut cracker embodying my new design, and

Figure 2 is a top plan view thereof.

My design for a nut cracker is characterized by the flat-eared, flatsided upstanding figure element in association with the log and leaf-shaped element, all as shown.

I claim:

The ornamental design for a nut cracker, as shown and described.

HERMAN E. COX.
